DESIGN FOR A HAMPER

William Fein, New York, N. Y.

Application April 7, 1938, Serial No. 76,351

Term of patent 7 years

To all whom it may concern:

Be it known that I, William Fein, a citizen of the United States of America and resident of the county of Kings, city and State of New York, have invented a new, original, and ornamental Design for a Hamper, of which the following is a specification, reference being had to the accompanying drawing, forming a part thereof.

In the drawing the figure is a view in perspective of the hamper showing my new design, the rear face being substantially plain and the opposite end being substantially the same as the end shown.

The characteristic features of the design reside

in a hamper of the configuration shown having a top portion and a panel member, both being of the same smooth surface finish and of the same color and contrasting in color with the body of the hamper; the panel being centrally located and vertically disposed on the front face of the hamper and being surrounded by a contrasting border frame, spacing it distinctively apart from the adjacent wicker body portions on opposite sides thereof.

I claim:

The ornamental design for a hamper, substantially as shown and described.

WILLIAM FEIN.
